burg, Mass., a corporation of Massachusetts

Application October 6, 1936, Serial No. 104,250

8 Claims. (Cl. 144—176)

This invention relates to an apparatus for producing wood sawdust, shavings, excelsior, etc. in commercial form and the commercial utilization of an otherwise waste product thereby.

5 The principal objects of the invention are to provide for the cutting of wood, preferably waste pieces, into whatever shape and form is desired; to provide a machine which can be made or adjusted in different forms so that the cutting 10 will be done at different angles to the grain, thereby producing different products, such as sawdust, long shavings, short shavings, excelsior, etc.; to provide means whereby slabs, edgings, or other mill products can be converted into any 15 form of wood in small pieces; to provide an improved form of hopper adjustable for feeding the wood to the cutters at the desired angle; to provide means for preventing a small piece of wood caught in the bottom of the hopper from 20 escaping without going through the knives; to provide a chute with automatic means for feeding a plurality of slabs, limbs, or the like, longitudinally by a reciprocating motion, and to provide a piston head of such shape as to properly 25 push the wood against the knives.

Other objects and advantages of the invention will appear hereinafter.

Reference is to be had to the accompanying drawings, in which

30 Fig. 1 is a longitudinal central sectional view of a machine constructed according to this invention;

Fig. 2 is a similar sectional view, on enlarged scale, showing the cutting operation to reduce 35 a piece of wood into shavings;

Fig. 3 is a face view of a circular cutter plate constituting a part of this machine;

Fig. 4 is a radial sectional view of the cutter plate;

40 Fig. 5 is a sectional view of an end bearing showing the hydraulic pump used in this invention;

Fig. 6 is a side view of a preferred form of feed chute in which the wood is presented to the 45 knives at a 60° angle for the production of short shavings;

Fig. 7 is a side view showing a feed chute that can be applied to Fig. 6;

Fig. 8 is a face view of a knife adapted to be 50 used on this machine;

Fig. 9 is a sectional view of the same on the line 9—9 of Fig. 8;

Fig. 10 is a view similar to Fig. 8 showing another form of knife adapted to be used on this 55 machine;

Fig. 11 is an end view thereof; and
Fig. 12 is an edge view of the same knife.

By this apparatus slabs, edgings or other mill by-products are introduced into a chute and cut up in that chute by rotating blades so that the 5 fine wood products, which may be in the form of long or short shavings, excelsior, etc. will be produced.

The form of wood product is controlled by the shape of the cutting edge of the knives and 10 angular position of the chute relative to the knives. In that form shown in Figs. 1 to 4 inclusive, the axis of rotation of the cutter is horizontal. The machine is supported by a base 10 on which are mounted two bearings 11 and 12 15 carrying the main shaft 13 which may be coupled directly with the main shaft of a motor 14. The bearings 11 and 12 are carried in casings mounted on the base.

The main shaft 13 carries a cutter head 15 20 which revolves in a stationary casing 16. On the base is a block 17 on which through screws 18 a slide 19 is adjustable. A chute, which comprises a back 21 and sides 20 mounted on the slide 19, has an open front facing the flat end of the 25 cutter disc 15. The top and sides of the chute are cast integral but the back 21 of the chute is hinged by means of a series of slots 22 in the sides of the chute and two pins on the back 21. The back of the chute is free to slide to and away 30 from the cutter disc 15 along the block 17. The loosely hung back, which fits closely between the sides of the chute, is held up in position by springs 23 threaded on rods 24. By means of check nuts 25 the rods provide for the adjustment of 35 the minimum position of the back. These nuts also prevent the back from contacting with the knives.

The cutter disc 15 is shown as provided with six generally radial openings 26 with inclined 40 sides and six knives 27 and 31 also running in a general radial direction and bolted to the sides. For the purpose of reducing the friction loss and the abrasions on the front surface of the cutter head a hardened steel insert 28 is located 45 in the front of each opening. The hardened steel insert has a tapered surface at 29 so that the end opposite the cutting edge is a small distance above the plate surface. The cutting knives 27 and 31 are arranged at quite an angle 50 to the flat surface of the disc and the way in which a shaving is cut off from a piece 30 of wood is illustrated in Fig. 2.

A construction is shown in which six knives are equally spaced around the disc. Three of these 55

are the plain cutting knives 27 and the other three knives 31 have their cutting edge interrupted by grooves to form a series of chisel points 32. With this construction and arrangement and 5 with the knives set with their cutting edges set at a short distance beyond the wear strips 28 the product will be sawdust when used in connection with Fig. 6. When used with Fig. 1 with all the edges of all the blades straight, the product is 10 shavings. With other arrangements other products can be made, as long shavings, excelsior, etc.

According to an application filed in the name of William O. Forman, October 25, 1937, Serial No. 170,823, but not a part hereof, the bark is 15 broken up into dust while the wood shavings tend to cling together to some extent and the bark has a chance to escape from it. On the back of the cutter head preferably are radial ribs 34 which act as an impeller. This, in conjunction with the volute casing formed by the shield 16 and a recess 16^a in the main casting, creates a very satisfactory blower which conveys the 20 processed material to any desired point by means of standard sheet metal piping.

25 It has been found by experiment that if the lower end of the back 21 of the feed chute is cut off parallel to the face of the disc, as shown at 33', the wood will be assisted in being drawn toward the cutter. With the knives set at a 30 sufficient distance beyond the strips on the face of the disc, any slab, limb, edging, or section of tree lumber that is dropped into the chute will be converted into sawdust or shavings and discharged by the centrifugal blower.

35 So far only one form of the apparatus has been described, the one in which the axis of the shaft is horizontal with an acute angle between it and the chute and alternating continuous cutting edge and toothed cutting edged knives are used. 40 Obviously, all the knives can be of either type. The angle between the axis of the cutter shaft and the direction of the feed of the wood changes the product materially.

45 It has been found by experiment that, if a horizontal feed chute is used and material fed to the disc with its grain running at right angles to the axis of the shaft and blades set so that they will cut the material, the wood is cut into wide, fairly straight shavings.

50 A preferred form of feed chute is shown in Fig. 6. This is arranged in such a manner that the wood is presented to the knives at an angle of approximately 60°. Although not necessarily so this particular chute is provided with cutters 55 having alternately serrated and straight edges to produce sawdust but short shavings would be produced if all the cutters were plain. The chute is provided with a movable end 35 or piston convex on the end operated by a feed cylinder 36 connected with the end through a piston rod 37. Attached to the end of a bearing opposite the drive pulley is a commercial gear pump 38 which is driven from the end of the main shaft, not shown in Fig. 6 but like the shaft 13. This pump 65 is arranged to run constantly at all times when the machine is in operation and pumps the operating fluid, as oil, from the reservoir 33, and delivers it to a four-way manually operated valve 39 which is attached to the side of the chute. A 70 predetermined pressure is maintained on the system by means of a conventional spring-loaded relief valve 40 discharging back into the reservoir 33. The manually operated valve 39 is so arranged that when it is thrown into the proper 75 position to feed the sticks or slabs toward the

rotating knives, it is latched by a weighted lever 42 and remains latched until the movable end or piston 35 has gone practically its extreme travel. At that time a projection 43 on the piston 35 engages the latch and unlatches it. This latch is spring-operated into such a position that the movable piston 35 returns to the loading position. 5

In connection with the form of feed shown in Fig. 6, a preferred arrangement can be used for keeping the wood up against the knives. This is shown in Fig. 7 and it involves the sides and front 45 of a chute open at the bottom along an inclined surface 46 and having a pair of integral bars 47 which support the rod 24 and the spring 23 and nuts 25 shown in Fig. 2. This rod is 10 pivotally connected with the back 48 of the chute. This back, which controls the position of the wood as it approaches the cutter, is cut off at 53 to form a surface parallel with the face of the cutter disc as previously described. In this case also 15 the back 48 can be supported by pins 49 entering into either one of a set of inclined slots 50 in the sides 45 of the chute.

Having thus described our invention and the advantages thereof, we do not wish to be limited 20 to the details herein disclosed, otherwise than as set forth in the claims, but what we claim is:

1. An apparatus for reducing wood to small 25 particles which comprises a rotary cutter having a flat face perpendicular to its axis and a chute 30 arranged to feed rough wood to the cutter with its grain at an acute angle of less than 45° to the plane of the face of the cutter, the cutter comprising knives set at a material angle to the face of the cutter to make long shavings. 35

2. An apparatus for reducing wood to small 40 particles which comprises a rotary cutter having a flat face perpendicular to its axis, a chute arranged to feed rough wood to the cutter with its grain at an angle to the plane of the face of the cutter, the cutter comprising knives projecting from the face of the cutter, and means for varying the angle to minute degrees at which the wood engages the cutter to determine the character of the product. 45

3. An apparatus for reducing wood to small 50 particles which comprises a rotary cutter having a flat face perpendicular to its axis and a chute arranged to feed rough wood to the cutter with its grain at a small angle to the plane of the face 55 of the cutter, the chute having a spring pressed back plate movable to different angles, and adjustable means for determining the clearance between the back plate and cutters.

4. An apparatus for reducing wood to small 55 particles which comprises a rotary cutter disc having a flat face perpendicular to its axis and a chute arranged to feed rough wood to the cutter with its grain at an angle to the plane of the face of the cutter, the chute having a back plate, 60 the end of which nearest the cutter is flattened off to be parallel to the face of the cutting disc.

5. In an apparatus for the purpose described, the combination of a hopper in inclined position, a piston in the hopper for feeding wood having a 65 convex-toothed operating end for engaging the wood, hydraulic means for feeding the plunger, a horizontal rotary shaft, a disc on the shaft arranged at right angles thereto, and knives on the face of the disc arranged radially and projecting 70 through the disc angularly.

6. An apparatus for reducing wood to small 75 particles which comprises a rotary cutter having a flat face perpendicular to its axis and a chute in inclined position arranged to feed rough wood

to the cutter with its grain at an angle to the plane of the face of the cutter, a piston in the chute having a convex coarsely toothed working surface, automatic hydraulic means for moving the piston on its operative stroke, a valve for keeping the piston in communication with a source of power, a latch for holding the valve open, and means for automatically releasing the latch to permit the piston to move back.

7. An apparatus for reducing wood to small particles which comprises a rotary cutter having a flat face perpendicular to its axis, a chute arranged to feed rough wood to the cutter with its grain at an angle to the plane of the face of the cutter, the chute having a swing adjustable back plate, means for limiting the movement of the back plate toward the cutter to a position far enough from the cutter to receive the wood, and

yielding means for constantly pushing the back plate toward the cutter.

8. An apparatus for reducing wood to small particles which comprises a rotary cutter having a flat face perpendicular to its axis, a stationary chute arranged to feed rough wood to the cutter with its grain at an angle to the plane of the face of the cutter, the chute having a series of pairs of perforations in its sides, a swing adjustable back plate for engaging the wood adapted to be pivoted at its top in any arc of said pairs of perforations, means for limiting the movement of the back plate toward the cutter, and yielding means for constantly pushing the back plate toward the cutter.
